UNITED STATES PATENT OFFICE.

WALTER JOHN FORD, OF DEPTFORD, LONDON, ENGLAND.

SAFE, MONEY-BOX, AND THE LIKE.

1,101,735.

Specification of Letters Patent. Patented June 30, 1914.

Application filed May 22, 1913. Serial No. 769,222.

To all whom it may concern:

Be it known that I, WALTER JOHN FORD, a subject of the King of Great Britain, residing in Deptford, London, England, have invented certain new and useful Improvements in or Relating to Safes, Money-Boxes, and the like, of which the following is a specification.

This invention relates to safes, money boxes and the like and has particular reference to what is known as slot mechanism for use therewith, this mechanism comprising a tilting platform for the coins, arranged contiguous to the slot in the safe through which the coins are inserted.

The chief object of the present invention is to so construct the slot mechanism that while permitting the free entry of a coin into the safe or box, it will more effectively prevent the money from being surreptitiously extracted than heretofore.

According to this invention, the aforesaid tilting platform is under the control of a safety device which moves with a manually operated shutter for closing the coin slot in the safe, in such manner that unless the shutter is in the closed position the safety device prevents the platform from being depressed. For this purpose the safety device may be in the form of an inclined lip or projection which moves with the shutter, and cooperates with the platform to prevent it from being depressed when the shutter is being moved to and from its closed position, but when the shutter is closed, occupies a position to render the platform free to tilt and permit the coin thereon to enter the safe. In order to prevent the possibility of a wire being inserted through the coin slot when the shutter is nearing its closed position for the purpose of depressing the platform and extracting the coins, a tongue or the like may be provided inside the safe contiguous to the end of the slot representing the closed position of the shutter. This tongue may be of any suitable length and is so arranged that the shutter overlaps it during that period of its movement when the aforesaid lip or projection is releasing the tilting platform.

In order that the said invention may be clearly understood and readily carried into effect the same will be described more fully

with reference to the accompanying drawings in which:—

Figure 1 is a front elevation of the upper portion of a safe showing the aforesaid shutter half open. Fig. 2 is a transverse section. Fig. 3 is a longitudinal section and Fig. 4, is a sectional plan (viewed from below) showing the improved mechanism which is represented in the position it occupies when the shutter is fully closed.

A represents the casing of the safe and A¹ the slot through which the coins are inserted.

B represents the tilting platform which is mounted on a pivot pin B¹ carried in lugs C¹ of a crown piece C riveted or otherwise attached to the underside of the top of the safe.

D represents the aforesaid shutter rotatably mounted on the crown piece C and having a slot D¹ which, when the shutter is in the open position registers with the slot A¹. The said shutter is provided with an external finger piece d by means of which it is actuated to cover and uncover the coin slot A¹. The said shutter also carries the aforesaid lip or projection D² which, as is shown in Fig. 3, is inclined in such a manner that so it lies more or less parallel to the platform when the latter is in its unrestrained and tilted position (i. e. when the shutter is fully closed) and permits the platform to rock about the pivot pin B into the position shown in full lines in Fig. 3. On moving the said lip or projection from the position shown in Fig. 3, in the act of opening the coin slot, it will tilt the platform into the position shown by broken lines and positively hold it in that position. The portion of the shutter that is immediately in rear of the platform when the shutter is in the closed position is preferably extended as shown at d² in Fig. 3, to form a screen, the said extension being of such a length that it leaves a gap e between its lower end and the platform which is no wider than is required to enable the largest coin intended to be used to pass therethrough. In this manner it is rendered difficult for the coins already in the safe to be surreptitiously caused to reach the upper side of the platform and be thereby extracted.

The crown piece C is formed with the aforesaid tongue C² (Fig. 1) which is ar-

ranged in line with the slots A¹, D¹. As is seen in Fig. 1, the said tongue closes the right hand end of the slot A¹, so that when the shutter D is moved to the right, during 5 closing, until the end thereof is in line with the end of the tongue, the slots A¹, D¹, are closed. The further movement of the shutter D toward the right brings the lip or projection D^x into the position shown in Fig. 3, 10 so that the platform can assume the open position shown in full lines in that figure, and thus permit a coin resting thereon and previously introduced into the open coin slot to pass through the gap e and fall into the 15 safe.

Claims:

1. Coin slot mechanism comprising a tilting platform, a manually-operated revolvably mounted shutter closing the coin slot 20 and means on said shutter preventing the tilting of the platform until the shutter is closed.

2. Coin slot mechanism comprising a tilting platform, a manually-operated revolvably-mounted shutter closing the coin slot, 25 and a lip upon said shutter preventing the tilting of the platform until the shutter is closed.

3. Coin slot mechanism comprising a tilting platform, a manually operated shutter closing the coin slot, means upon said shutter preventing the tilting of the platform until the shutter is closed, and an extension 30 on the shutter at the rear of the platform 35 to prevent the passage of coins larger than those of a predetermined value.

4. Coin slot mechanism comprising a tilting platform, a manually operated shutter closing the coin slot, a lip inclined so that 40 it lies parallel to the tilting platform when the latter is opened preventing the tilting of the platform until the shutter is closed, and an extension on the shutter at the rear of the platform to prevent the passage of 45 coins larger than those of a predetermined value.

5. Coin slot mechanism comprising a tilting platform, ears upon the underside of said platform, a body secured to the top of 50 the box having a peripheral wall, ears upon said wall, a pivot passing through the ears on the tilting platform and on the wall, a shutter for the coin slot comprising a circular revolvably mounted shutter closing the coin slot, and a lip upon said shutter preventing the tilting of the platform until the shutter is closed, said lip being so inclined as to lie 55 parallel with said platform when the latter is opened.

upon the revolvble body, a lip upon said body engaging the underside of the platform, and a projection on said body extending through the coin slot.

6. Coin slot mechanism comprising a tilting platform, ears upon the underside of said platform, a body secured to the top of the box having a peripheral wall forming an abutment for the rear of the tilting platform to limit its upward movement, ears upon said wall, a pivot passing through the ears on the tilting platform and on the wall, a shutter for the coin slot comprising a circular revolvble body having at its upper end an inwardly directed flange engaged by the body on the top of the box, a vertical wall upon the revolvble body, a lip upon said body engaging the underside of the platform, and a projection upon said body extending through the coin slot.

7. Coin slot mechanism comprising a tilting platform, ears upon the underside of said platform, a body secured to the top of the box having a peripheral wall forming an abutment for the rear of the tilting platform to limit its upward movement, ears upon said wall, a pivot passing through the ears on the tilting platform and on the wall, a shutter for the coin slot comprising a circular revolvble body having at its upper end an inwardly directed flange engaged by the body on the top of the box, a vertical wall upon the revolvble body, a lip upon said body engaging the underside of the platform, a projection upon said body extending through the coin slot, and an extension on the rear part of the wall of the shutter forming a screen whereby the passage 85 of coins of larger size than those of a predetermined value is prevented.

8. Coin slot mechanism comprising a tilting platform, a manually-operated revolvably-mounted shutter closing the coin slot, and a lip upon said shutter preventing the tilting of the platform until the shutter is closed, said lip being so inclined as to lie 100 parallel with said platform when the latter is opened.

In witness whereof I have hereunto signed 105 my name in the presence of the two undersigned witnesses.

WALTER JOHN FORD.
